Filed Jan. 15, 1964, Ser. No. 78,211

Term of patent 14 years

(Cl. D33—6)

The back of the chest is substantially plain and unornamented.

I claim:

The ornamental design for a chest, substantially as shown and described.
